United States Patent Office.

MARTIN LANDENBERGER, OF PHILADELPHIA, PENNSYLVANIA.

Design No. 4,270, dated August 2, 1870.

DESIGN FOR A KNITTED FABRIC.

The Schedule referred to in these Letters Patent and making part of the same

To all whom it may concern:

Be it known that I, MARTIN LANDENBERGER, of Philadelphia, in the county of Philadelphia and State of Pennsylvania, have invented and produced a new and original Design for Knitted Fabric, of which the following is a specification.

The nature of my design is fully represented in the accompanying photographic illustration, to which reference is made, and consists in an imitation of ermine, which may be of any color, and used for shawls, goods, childrens' muffs, and tibbits, trimming for garments, &c.

Figure 1 shows bottom of goods.

Figure 2 represents top of goods with loops thrown part, showing mode of tying.

Figure 3 is a plan view.

Figure 4 is a view showing how the stitch is made. This stitch is made on a double-rib machine, with two needle-bars and two guide-bars. The needle-bars are placed as far apart as the length of the loop requires. The needles on these bars rise and fall alternately, that is, one bar rises as the other falls.

The novelty of this stitch lies in the fact that it is made on self-acting needles, and that the threads forming the ruche lap on every other needle in the bar alternately, making a loop on half the needles, while the other half presses off, as will be understood on reference to fig. 4.

Let the dots *aa* represent the needles, No. 1 being back bar, and No. 2 the front bar. Let the black

line mark the course of one thread through one revolution of the machine, and the red line mark the course of the same thread through the next revolution.

The thread will start from A in the back bar, lap around D in the front bar, and go back and lap on A, which completes one revolution.

Then it begins at B, laps around C, and goes back and laps on A, which completes the second revolution.

Now, when the thread islapping over D in the first revolution, there is a loop on C, but as soon as the needles go down there is a loop on D, and C has pressed off; and when the thread laps over C, and the needles go down, the loop which remains on D presses off and C has another loop.

Besides these threads, there are others,lapping from one needle to another, in the back bar, making a plait stitch, which serves to hold the work firmly together.

What I claim is—

The design for knitted fabric, as shown and described.

In testimony whereof I have signed my name to this specification in the presence of two subscribing witnesses.

MARTIN LANDENBERGER.
